UNITED STATES PATENT OFFICE.

FRANK C. MORGAN, OF CHICAGO, ILLINOIS.

DESIGN FOR A HEEL-LIFT.

SPECIFICATION forming part of Design No. 32,263, dated February 20, 1900.

Application filed January 15, 1900. Serial No. 1,565. Term of patent 14 years.

To all whom it may concern:

Be it known that I, FRANK C. MORGAN, a citizen of the United States, residing at Chicago, county of Cook, State of Illinois, have invented and produced a certain new and original Design for Heel-Lifts, of which the following is a specification, reference being had to the accompanying drawings, forming part thereof.

In said drawings, Figure 1 is a plan of the heel-lift. Fig. 2 is a perspective of the same.

The heel-lift shown is formed with a relatively-thin marginal portion 1 and a relatively-thick central portion 2. The outline of the said marginal portion corresponds, it will be observed, with the outline of an ordinary shoe

or boot heel. Said central portion has its rear end rounded, as at 3, and its sides indented or notched, as at 4. The forward end 5 of said central portion is slightly concave. The 20 surface of this relatively-thick portion is roughened or corrugated, substantially as shown.

Having described my invention, what I claim as new, and desire to secure by Letters 25 Patent, is—

The design for a heel-lift, substantially as shown and described.

FRANK C. MORGAN.
